FASTENER ORNAMENT

Harold S. van Buren, Jr., Cambridge, Mass., assignor, by
mesne assignments, to United-Carr Fastener Corpora-
tion, Boston, Mass., a corporation of Delaware

Application May 18, 1953, Serial No. 355,432

2 Claims. (Cl. 24—216)

This invention relates generally to ornaments and has
particular reference to a removable ornament and orna-
ment assembly for use on shirts or the like.

Ornamental buttons and the like are frequently used
on shirts and other garments which are subjected to
laundering and dry cleaning and are often damaged
thereby. Many types of ornamental materials such as
plastic cannot withstand the temperatures or cleaning
solutions used in such operations, and other materials,
such as salt water or fresh water pearls cannot withstand
pressing operations.

Many types of removable ornaments have been pro-
posed for such applications. Such ornaments have not
had any great commercial success heretofore, particularly
on garments utilizing snap fasteners, since when the snap
fasteners retaining the garment closed are unsnapped by
pulling on the cloth adjacent the fastener, the cloth fre-
quently causes the removable ornament to become dis-
engaged also.

The use of such removable ornaments has also been
hindered by the fact that the means permanently as-
sembled onto the garment for receiving the removable
ornament is usually unsightly when the ornament is not
assembled thereon, and by the bulkiness and unsightly
appearance of the means for securing the removable
ornament to the shirt.

The object of the invention is to provide a removable
ornament for use on shirts and the like, which may be
used on garments using snap fasteners as closure means.

A further object of the invention is to provide an
ornamental assembly for use on shirts and the like in
which there is no tendency of the ornamental member
to become accidentally disengaged.

A still further object of the invention is to provide a
removable ornamental device for use on shirts or the like,
in which a cylindrical body formed of a single piece of
sheet metal has means at one end retaining an ornamental
center portion and means at the other end for engaging a
suitably shaped button attached to the garment.

Other objects of the invention will, in part, be obvious,
and will, in part, appear hereinafter.

In the drawing:

Fig. 1 is a perspective view of an ornament embodying
the features of the invention;

Fig. 2 is a top plan view of a metallic button member
attached to a shirt for receiving the ornament of Fig. 1;

Fig. 3 is a top plan view of the ornament assembled
onto the button;

Fig. 4 is a view in section taken on line 4—4 of Fig.
3; and

Fig. 5 is an enlarged view in section of the assembled
ornament illustrating the effect of pulling on the cloth
adjacent the ornament.

Referring to the drawing, there is illustrated an orna-
mental assembly 10 for use on a shirt 12 or the like,
which comprises a button 14 and a snap fastener 16 for
assembly onto opposite sides of the shirt material, and
an ornament 18 for assembly onto the button 14.

2

The button 14 comprises generally a head 20 which is
substantially circular, with a smoothly rounded peripheral
edge 22, and a shank 24 projecting therefrom to pierce
the shirt material and engage a button retaining device,
such as the snap fastener stud 16 disposed on the side of
the material opposite the head. The button is assembled
tightly onto the shirt material so that it projects only a
short distance above the surface thereof.

The ornament 18 comprises a cylindrical body portion
26 having a radially extending flange 28 near one end
and an inwardly curled end portion 30, forming a peripheral
recess 32, in which is retained the periphery of an
ornamental center portion 34, which may be formed of
plastic, salt water or fresh water pearl, or any other
desired ornamental material.

The other end of the cylindrical body 26 is provided
with a button engaging portion 36, which extends a short
distance radially inwardly and is connected to the cylind-
rical body portion by a smoothly rounded portion 38
which conforms generally in shape to the smoothly
rounded peripheral edge 22 of the button. In the pre-
ferred embodiment, the button engaging portions 36
decrease in thickness toward the innermost edges thereof.

To enable the ornament 18 to engage the button 14, a
series of slits 40 are provided in the cylindrical portion
which extend longitudinally therein and also extend to
the innermost edge of the button engaging portions.

The cylindrical portion is thereby provided with
sufficient expansive resilience to enable the button engag-
ing portions to cam over the outer periphery of the button
and seat underneath the edge thereof, with the smoothly
rounded portions seating against each other (see Fig. 5).
Hence, the ornament may be easily assembled and re-
moved with the fingers. However, as shown in Fig. 5,
it cannot become accidentally disengaged when the shirt
material is pulled outwardly to disengage the snap fastener
stud 16 from a snap fastener socket (not shown) on an-
other portion of the garment, since the material, during
such operation, bears against the end of the cylindrical
portion of the ornament and forces it more tightly against
the button.

The snap fastener stud 16 illustrated herein is merely
representative of one type of device which may be utilized
to retain the button in assembly on the shirt. In some
cases, a snap fastener socket, or various other types of
fastening devices, may be used.

Since certain other obvious modifications may be made
in the device without departing from the scope of the in-
vention, it is intended that all matter contained herein be
interpreted in an illustrative and not in a limiting sense.

I claim:

1. A removable ornament for shirts and the like, com-
prising an ornamental center portion and an attaching
portion assembled therewith, said attaching portion being
formed of resilient material and comprising a generally
cylindrical body having radially outwardly extending
means at one end forming a peripheral recess to receive
and retain the periphery of an ornamental center portion
therein, the other end of said body having radially in-
wardly extending end portions, said end portions decreas-
ing in thickness toward the innermost edge thereof, and
a series of slits extending longitudinally from said other
end to provide a snap fastener portion for snap engage-
ment with a cooperating fastener portion, said cylindrical
body being substantially peripherally continuous except
for said slits.

2. An ornamental assembly for use on shirts and the
like, comprising a metallic button member for attach-
ment to the shirt, and a removable ornament for snap
fastener assembly onto the button, said button having a
head portion for seating against one side of the material
and a shank extending from the head for piercing the

material to engage a button retaining device on the opposite side thereof, said head portion being substantially circular and having a smoothly rounded peripheral edge, said removable ornament comprising a generally cylindrical body having radially outwardly extending means at one end forming a peripheral recess for receiving and retaining the periphery of an ornamental center portion, the other end of said body having radially inwardly extending end portions, said end portions decreasing in thickness toward the innermost ends thereof, and a series 10

of slits extending longitudinally from said other end to provide a snap fastener button engaging portion for seating under the rounded peripheral edge of the button.
